UNDERWATER EXHAUST

Donald S. Willy, North Quincy, Mass., assignor to Submarine Research Laboratories, Inc., Everett, Mass., a corporation of Massachusetts

Filed Aug. 21, 1962, Ser. No. 218,400

1 Claim. (Cl. 115—5)

This invention relates generally to exhaust systems for internal combustion engines, and more particularly to demountable means structurally independent of a marine engine exhaust assembly for directing the exhaust gases under the surface of the water over which the vessel is passing.

In the construction of marine exhaust systems, two principal types have heretofore been known. One such type is a "dry" exhaust system in which a suitable exhaust pipe is attached to the engine exhaust manifold and is usually positioned in a generally vertical fashion, being vented to the atmosphere. In such a system a conventional muffler is customarily required to provide sufficient silencing. It is important that the exhaust pipe be not confined in any fashion to insure that heat dissipated from the exhaust pipe and muffler will not set fire to adjacent portions of the vessel.

A second type of marine exhaust system which is frequently employed is a "wet" exhaust system. One of the limiting features of a dry exhaust system is the difficulty involved in locating the exhaust pipe in other than a substantially vertically disposed position, so as to be in the open air, or in a ventilating stack. In a wet exhaust system the exhaust pipe generally runs with a slight downward slope from the engine toward the stern of the vessel, terminating in a flange or fitting affixed to the outer face of the transom slightly above the water line. In such a system it is necessary to add cooling water to the exhaust pipe in order to prevent the pipe from becoming dangerously hot, with consequent hazard of igniting adjacent portions of the vessel. The cooling water is usually taken from the engine cooling system and introduced into the exhaust pipe aft of the exhaust manifold. A water trap may be provided in the exhaust system between the exhaust manifold and the point of introduction of the cooling water to prevent backflow of the water into the engine.

The cooling water introduced into the exhaust system passes through the pipe and is discharged at the transom through the orifice formed at the end of the pipe. During operation of the engine the exhaust pipe is heated by the exhaust gases and a substantial portion of the cooling water is converted into steam. No muffler is generally employed in such systems since considerable muffling or silencing is accomplished through the introduction of the cooling water. During operation of the vessel, engine fumes and steam are consequently discharged from the exhaust system and can be observed rising from the stern of the vessel. When the wind is blowing from the proper direction, clouds of steam and exhaust fumes are swept over the stern producing an unpleasant condition for the occupants of the boat. In addition, there is apt to be objectionable exhaust noise, as engines of high horsepower are increasingly favored for power craft in order to achieve greater speed.

It is, accordingly, an object of this invention to provide an exhaust assembly for use with a wet exhaust system which will divert the exhaust gases under the surface of the water to silence the operation of the engine and simultaneously to reduce the presence of exhaust gases in the vicinity of the vessel.

It is a further object of this invention to provide an underwater exhaust of the type described for use with a wet exhaust system which will not interfere with the safe

2

operation of the engine nor will require modification of existing internal exhaust system structure.

It is likewise an important object of my invention to provide an effective underwater exhaust discharge attachment which will handle large volumes of exhaust gas without diminishing engine performance through the development of excessive back pressure.

In the practice of my invention, in a preferred embodiment thereof, I provide a duct member adapted for installation over the discharge orifice of a wet exhaust system which is normally located on the outboard side of the transom. The duct member is preferably constructed of a resilient material and extends from the discharge orifice in a generally vertical direction to a point located some distance below the surface of the water. The duct member is formed with an airfoil configuration to reduce drag and is cut away at its terminal portion to introduce the exhaust gases into the water in the most efficient fashion to minimize back pressure. Cavitation plates are provided below the waterline to prevent the formation of an air column behind the duct during forward movement of the vessel. Since the duct of my invention is attached to the outboard surface of the transom, no modification of the engine or internal engine exhaust system is required.

It is a feature of my invention that a high degree of silencing of engine noises is achieved with an accompanying high degree of reduction of exhaust fumes and steam in the general stern area of the vessel.

It is a further feature of my invention that no baffles or similar structures are employed in my silencer whereby no unwanted water will be retained in the system when the engine is stopped.

It is yet another feature of my invention that the duct of my invention is constructed of a resilient material having shock resistant characteristics.

It is still a further feature of my invention that the duct of my invention may be damaged, broken or removed without affecting the normal operation of the engine or its exhaust system.

These and other objects and features of my invention will appear as the description proceeds with the aid of the accompanying drawings, in which:

FIG. 1 is a side view of an underwater exhaust according to my invention shown in installed position;

FIG. 2 is an end view of my invention prior to installation;

FIG. 3 is a side view of the device of FIG. 2;

FIG. 4 is a section taken on the line 4—4 of FIG. 3; and

FIG. 5 is a section taken on the line 5—5 of FIG. 3.

Referring to FIG. 1 of the drawings for a more particular description of my invention in a preferred embodiment thereof, a fragmentary stern portion of a motor vessel 10 is shown. The motor vessel 10 includes a bottom 12 and a transom 14. An exhaust pipe 16 is shown in its usual position passing generally horizontally through the transom 14. It will be understood that the exhaust pipe 16 is part of a "wet" exhaust system in which cooling water is added to the exhaust pipe 16 to prevent overheating thereof. An end ring fitting or annular sealing flange 18 is positioned about the exterior of the exhaust pipe 16 and fitted against the outboard surface of the transom 14 to prevent the passage of water into the bilge.

An exhaust duct member, indicated generally at 20, is shown affixed to the transom 14. In the preferred embodiment, the member 20 is constructed of a resilient non-metallic material, as for example neoprene, rubber or the like. It will be understood, however, that the member 20 could be constructed of non-resilient material if the yielding shock-resistant qualities hereinafter de-

scribed in my invention are not desired. The member 20 is formed with internal ducting including a substantially hemispherical chamber 22 in direct communication with the exhaust outlet orifice 24 formed at the outboard end of the exhaust pipe 16. The hemispherical chamber 22 communicates through its bottom 26 with a substantially vertical duct 28.

The member 20 is provided at its upper end with means for securing it to the transom 14 comprising an integral flange plate 30. A plurality of spaced peripheral openings 32 are provided through the flange plate 30 whereby the member 20 may be bolted to the transom 14 of the vessel by bolts 34 which pass through the transom 14 and are retained by nuts 36. A gasket 38 or other packing may be interposed between the flange plate 30 and outboard surface of the transom 14 if desired.

The hemispherical chamber 22 communicates with the discharge orifice 24 of the exhaust pipe 16 through an opening indicated generally at 40 in the flange plate 30. The opening 40 is substantially the same radius as the hemispherical chamber 22 and may be provided with slightly outwardly inclined terminal portions 42. The size of the opening 40 is initially selected to permit the member 20 to be bolted to the transom 14 by its flange plate 30 and to completely cover the discharge orifice 24 of the exhaust pipe 16 and the annular sealing flange 18. In this fashion it is unnecessary to disturb or modify the existing exhaust system. A substantial advantage is derived thereby in that the member 20 may be removed at will from the vessel without interfering with the existing exhaust system and the safe operation of the engine.

The member 20 has a generally outwardly and downwardly curved external upper portion 44 which merges into a downwardly extending lower portion 46. A plurality of horizontal fins 48 are provided on the upper portion 44 and extend longitudinally from the flange plate 30 to the rearmost portion of the upper portion 44. In the preferred embodiment three such horizontal fins 48 are employed. Each fin 48 extends transversely substantially the full width of the flange plate 30 and is provided with a rearward semi-circular edge 50 as is best seen in FIG. 4. The horizontally extending fins 48 serve to absorb compression shocks which may be administered to the member 20, as for example by backing into a dock.

The lower, substantially vertical portion 46 of the member 20 extends when installed six to nine inches below the bottom 12 of the boat. Since the height of the exhaust orifice 24 above the bottom 12 of the vessel will vary from case to case, the member 20 is initially formed as seen in FIGS. 2 and 3 to include a vertical portion 46 which extends substantially further than is normally required. Since the member 20 is constructed, in the preferred embodiment, from a resilient material, as for example neoprene, it is an easy matter for the user to cut the member 20 to the proper length at the time of installation.

The member 46 has a generally tear-drop configuration producing a general airfoil shape as may be most clearly seen in FIG. 5. The airfoil shape greatly reduces the drag caused by the portion 46. The airfoil shape also greatly reduces the possibility of the formation of a vertical air column at the trailing edge 45 of the portion 46. The presence of such an air column would substantially defeat the operation of the member 20 since the steam and exhaust fumes would be permitted to rise directly to the surface and would not be carried away underwater, nor would the effective silencing result.

In order to further eliminate the possibility of the formation of an air column at the trailing edge 45 of the portion 46, a plurality of horizontally extending cavitation plates 54 are mounted on the member 46. As is most clearly seen in FIG. 5, each cavitation plate 54 extends rearwardly from the member 46 and terminates in a rounded rear edge 56. The cavitation plates 54 serve

5 to break up, deflect and dispel any air bubbles which may be formed during forward movement of the vessel.

The vertical passage 28 within the portion 46 extends the entire length thereof from the bottom 26 of the hemispherical chamber 22 to an outlet portion, indicated generally at 58 in FIG. 1. The outlet 58 is formed by first cutting the portion 46 horizontally from its trailing edge 45 approximately halfway through the passage 28 and by then cutting longitudinally up the member 46 from its bottom to the junction of the first cut. This forms a rearward opening or outlet in the member 46 through which the exhaust gases and steam are discharged under the water. The adjacent forward portion of the member 46 indicated generally at 60, is not removed or cut off at the time of installation. Adjacent the outlet 58 there therefore remains the portion 60 with its airfoil configuration including a leading edge 62. The presence of the portion 60 increases the flow of exhaust gases from the passage 28 by creating a slight reduction in pressure at the outlet 58 during forward movement by the vessel. It will be noted that this reduction in pressure is increased as the speed of the vessel relative to the water increases. The exhaust gases will therefore be expelled with substantially constant efficiency as the speed of the vessel increases relative to the water.

20 A relief port 64 may be provided in the member 20 to vent the hemispherical chamber 22 to the atmosphere. As seen in FIG. 1, the port 64 is located at the side of the member 20 just below the uppermost horizontal fin 48, whereby any spray rising from the port 64 is directed downwardly. The relief port 62 is not a necessary element in my invention but may be useful where the vessel's engine is located below the water line, under which conditions syphoning of water could occur. The relief port 35 64 may also be desired where substantial back pressure is present in the system rendering engine starting difficult. The relief port 64, which could be valved, may be approximately $\frac{1}{8}$ inch in diameter and in no way interferes with the proper operation of the member 20.

30 It should also be noted that the construction of the member 20 from a resilient material as in the preferred embodiment produces an additional advantage in that the member 20 will be deflected slightly by the water when the vessel is engaged in a high speed turn, thereby reducing drag components which otherwise would tend to oppose the rudder turning components. The resiliency of the member 20 is also advantageous in that the member 20 can sustain a degree of shock, as for example when the vessel is backed into a dock or other object. This resiliency is also valuable in that the member 20 will not fracture when the vessel strikes a submerged object, as for example a buoy.

40 The installation of my exhaust assembly is as follows:

The member 20 is initially constructed as shown in FIGS. 2 and 3. The vertical portion 46 is first trimmed to extend approximately 6 to 9 inches below the bottom of the boat. The exhaust outlet 58 is then cut in the vertical portion 46 as above described. The flange plate 30 is bolted to the transom of the vessel with the opening 40 leading to the hemispherical chamber 22 positioned over the exhaust orifice 24. As above noted, it is unnecessary to remove the annular sealing flange 18 normally positioned about the exhaust orifice 24. The unit is then ready for operation.

50 It will thus be observed that an underwater exhaust is provided by my invention which produces a high degree of engine silencing and a high degree of reduction of exhaust fumes and steam by discharging the fumes and steam substantially below the surface of the water where they may be carried rearward thereof. In the event of damage sustained to the underwater exhaust of my invention, it is further possible to remove it from the vessel without interfering with the safe operation of the engine.

What I claim as new and desire to secure by Letters Patent of the United States is:

An exhaust silencer device for a motor vessel having a hull through which an exhaust pipe for an inboard engine extends in a generally horizontal direction in the vicinity of the waterline of the vessel for discharge into the open air, said device comprising a body having a generally horizontal inlet passage and a generally vertical passage in communication therewith, the body having a flange for securing the device to the hull of the vessel over the open end of the exhaust pipe outwardly thereof with the inlet passage of the body aligned with the discharge passage of the exhaust pipe, the body of the device extending downwardly from the hull of the vessel to a region below the surface of the water when the vessel is under way, the cross-sectional configuration of the body below the surface of the water being elongated in a

fore and aft direction of the vessel, the body tapering toward its leading and trailing edges from a region intermediate said edges, the body at its bottom end being deeper toward its tapered fore part than in the trailing portion, the exhaust gas discharge passage extending vertically downward through the bottom of the body through both the deeper fore part and the trailing portion of said body.
